ELECTRONIC CALCULATING MACHINE

Yoshisaburo Yoshida, Shigetoshi Hazama and Yoshihisa
Ochiai, Osaka, Japan, assignors to Sharp Kabushiki
Kaisha, Osaka, Japan

Filed Feb. 27, 1974, Ser. No. 446,162

Claims priority, application Japan, Sept. 6, 1973

Term of patent 14 years

Int. Cl. D18—01

U.S. Cl. D26—5 C

FIG.—1

FIG.—3

FIG.—2

FIG.-4

FIG.-5

FIG.-6

FIG.-7

FIG. 1 is a front perspective view of an electronic calculating machine shown with the display cover raised showing our new design;

FIG. 2 is a plan view thereof shown with the display cover closed;

FIG. 3 is a front elevational view thereof;

FIG. 4 is a right side elevational view thereof;

FIG. 5 is a left side elevational view thereof;

FIG. 6 is a rear elevational view thereof; and

FIG. 7 is a bottom view thereof.

The broken line showing of the display in FIG. 1 is for illustrative purposes only and forms no part of the claimed design.

We claim:

The ornamental design for an electronic calculating machine, as shown and described.
